UNITED STATES PATENT OFFICE

149,659

DESIGN FOR A STOKER

Willard F. Manthei, Milwaukee, Wis.

Application April 13, 1946, Serial No. 128,572

Term of patent 14 years

(Cl. D81—2)

To all whom it may concern:

Be it known that I, Willard F. Manthei, a citizen of the United States, residing at Milwaukee, in the county of Milwaukee and State of Wisconsin, have invented a new, original Design for a Stoker, of which the following is a specification, reference being had to the accompanying drawing, forming part thereof.

Figure 1 of the drawing is a side perspective view of a stoker showing my new design, the other side of the stoker being substantially the same; and

Figure 2 is a rear elevational view of the stoker housing shown in Figure 1.

The dominant features of my design reside in the hopper shown in full lines.

I claim:

The ornamental design for a stoker, substantially as shown and described.

WILLARD F. MANTHEI.
